CLAIM

The ornamental design for a quick attachment stop member for a threaded feed rod of a machine tool, substantially as shown and described.

DESCRIPTION

FIG. 1 is a top perspective view of a quick attachment stop member for a threaded feed rod of a machine tool showing my new design;

FIG. 2 is a perspective view thereof as seen from the bottom and opposite end;

FIG. 3 is a perspective view thereof in open condition.

FIG-1

FIG-2

FIG-3
